[57] CLAIM

The ornamental design for a chemical dispenser for toilets, as shown and described.

DESCRIPTION

FIG. 1 is a front elevational view of a chemical dispenser for toilets showing my new design;

FIG. 2 is a right side elevational view thereof;

FIG. 3 is a rear elevational view thereof;

FIG. 4 is a left side elevational view thereof;

FIG. 5 is a plan view thereof;

FIG. 6 is a bottom view thereof;

FIG. 7 is a front elevational view of a modified form of the deodorizing dispenser for toilets shown in FIG. 1;

FIG. 8 is a right side elevational view of FIG. 7;

FIG. 9 is a rear elevational view of FIG. 7;

FIG. 10 is a left elevational view of FIG. 7;

FIG. 11 is a plan view of FIG. 7;

FIG. 12 is a bottom view of FIG. 7;

FIG. 1

FIG. 2

FIG. 3

FIG. 4

FIG. 5

FIG. 6

FIG. 7

FIG. 8

FIG. 9

FIG. 10

FIG. 11

FIG. 12
